UNITED STATES PATENT OFFICE

2,442,066

DIAPHRAGM INSERTER AND REMOVER

Carl C. Waterbury, Chicago, Ill., assignor to
Diaphragm & Chemical Company, Chicago,
Ill., a corporation of Illinois

Application June 22, 1945, Serial No. 600,935

5 Claims. (Cl. 128—127)

1

This invention relates to a device for inserting an expansible article through a small neck into a cavity where the article is to remain. More particularly this invention is directed to an inserter device of the type for facilitating the introduction and temporary placement of a flexible diaphragm into the vaginal canal in position to cover the mouth of the uterus.

One of the objects of the present invention is to provide a novel device of the character indicated, which may be easily and conveniently used to initially hold a diaphragm in proper position thereon preparatory to introduction into the vaginal canal, and which is adapted to readily disengage the diaphragm therefrom in a proper position in the canal.

Another object is to provide an improved device of the character indicated, which is composed of two telescopically and removably associated parts which may be conveniently cleansed or sterilized.

A further object is to provide an improved device of the character indicated, comprising two telescopically associated parts constructed and arranged with cooperating means for engaging diametrically opposite marginal portions of a flexible diaphragm for holding it in a stretched position preparatory to placement in the vaginal canal, and wherein the resiliency of the diaphragm is utilized in its stretched condition to yieldingly retain said parts in operative relation.

Still another object is to provide an improved device of the character indicated which is of simple construction and lends itself to relatively economical manufacture, and is capable of being efficiently used for the intended purpose either by physicians, nurses or unskilled persons.

Other objects and advantages of this invention will be apparent from the following description, taken in connection with the accompanying drawing in which:

Figure 1 is a side elevational view of the device embodying the present invention;

Figure 2 is a plan view;

Figure 3 is a view, part in section and part in elevation, and showing a diaphragm supported thereon in operative stretched condition;

Figures 4 and 5 are transverse sectional views through the device, taken substantially as indicated at line 4—4 and 5—5, respectively, on Figure 3;

Figure 6 is an elevational view of the movable sleeve of the device, having a plurality of detents; and

Figure 7 is a cross sectional view through a

2

conventional form of diaphragm in its normal condition.

The device embodying the present invention is composed of only two main separable parts, namely, an elongated body member indicated generally at 10, and a tubular sleeve member 11. These parts may be made out of any suitable material such as metal or plastic, and because of their construction may, as will hereinafter appear, be quickly and easily separated so as to be conveniently cleansed and/or sterilized.

The body member 10 includes a cylindrical shank portion 14, connected at one end to a downwardly tapering head 15 which is of generally flattened cross section, as may be clearly seen in the drawing. The outer end of the head terminates in a pair of outwardly diverging prongs 16 and 17, forming a generally V-shaped socket or seat 18, into which may be seated the marginal portion of a flexible diaphragm, indicated at 20. The opposite end of the head terminates in a transverse shoulder 22 which is adapted to serve as a stop for the tubular member 11 when the latter is telescopically mounted on the shank 14. The shape of the head 15 and its relation to the shank 14 are such as to afford maximum convenience in using the device in a manner so as to preclude the possibility of injury to the delicate tissues.

30 The tubular member 11 is provided with an aligned series of upwardly extending projections or detents 24. When a marginal portion of the diaphragm is seated in the socket 18 of the head, the diametrically opposite marginal portion of said diaphragm may be seated selectively behind one of the detents 24 for anchoring the diaphragm in a proper stretched position on the device, as may be seen in the drawing. Extending laterally and rearwardly from the tubular member 11 is a

40 lug or finger piece 26 for rotating the tubular member to disengage the detent from the diaphragm, as hereinafter described. It will be observed that the operative or rear face of each of the detents is curved transversely so as to provide

45 substantially a line contact when engaged by the marginal portion of the diaphragm, and thus reduce to a minimum the frictional resistance present and which must be overcome in disengaging the detent from the diaphragm.

50 The purpose of the plurality of detents is to accommodate various sizes of diaphragms. Such diaphragms are usually covered with an antiseptic jelly or lubricant which would normally render them difficult to handle in the proper placement of the diaphragm. In use the dia-

55 phragm is seated in the socket 18 and the tubular member 11 is slid over the shank 14 until the shoulder 22 rests against the head 15.

phragm is first seated at one marginal edge in the socket 18 at the outer end of the head 15 of the device, and the diametrically opposite marginal portion is then seated selectively in back of one of the detents 24 of the tubular member 11. It is preferable, in the application of the diaphragm to the device, that it be first stretched in oblate form, as seen in the drawing, and then anchored in back of the nearest aligned detent, so as to maintain the diaphragm in stretched formation. By virtue of this arrangement the resiliency of the diaphragm serves to yieldingly retain the tubular member 11 in abutting engagement with the shoulder 22 of the head.

When the device has been inserted, with the diaphragm thereon, into the vaginal canal, in the proper position, the finger piece or lug 26 may be engaged to rotate the tubular member 11 to a position as seen in dot and dash outline in Figures 3 and 5 for effecting disengagement of the particular detent 24 with respect to the marginal portion of the diaphragm 20 so as to permit the diaphragm to be released and remain in the vaginal canal in a proper position. Due to the construction of the device it is possible, by grasping the outer end of the shank 14, to hold the entering end of the diaphragm behind the cervix while the diaphragm is being disengaged, so as to be certain of placement of the diaphragm exactly where desired. It will be apparent that in the use of the device there will be no possibility of a part of the device becoming disconnected and left in the vaginal tract.

The hook shaped prongs 16 and/or 17, at the outer end of the head, may be utilized to facilitate the removal of the diaphragm from the vagina, in a well understood manner.

It is to be understood that the diaphragm, as illustrated in the drawings and as indicated by the reference numeral 20, is of a conventional form, made of relatively thin, flexible, resilient material such as latex, and is usually formed at its marginal edge with a resilient member such as a relatively small coil spring, as indicated at 20a, or said resilient member may be in the form of a rubber cord or ring which tends to maintain the diaphragm in proper form, but permits deformation, such as by stretching, when mounted on the inserter device.

Although I have herein shown and described a preferred embodiment of my invention, manifestly it is capable of modification and rearrangement of parts without departing from the spirit and scope thereof. I do not, therefore, wish to be understood as limiting this invention to the precise form herein disclosed, except as I may be so limited by the appended claims.

I claim as my invention:

1. In an introducer, the combination of an elongated body having means at its forward end for seating a marginal portion of a diaphragm, said body having a transverse bearing shoulder adjacent the forward portion thereof, a sleeve rotatably and removably mounted on the opposite portion of the body in abutting relation to said shoulder, a detent on said sleeve adapted for engaging the opposite marginal portion of the diaphragm for holding it stretched, and thereby yieldingly holding the sleeve in abutting engagement with the shoulder, and means extending laterally and rearwardly from said sleeve for rotating it and the detent for disengaging the diaphragm therefrom.

2. In an introducer, the combination of an elongated body including a cylindrical shank and

a head portion, a shoulder on the body at the junction of the head and shank, the extended end of said head having means for seating a marginal portion of a diaphragm, a sleeve mounted on said shank and removable from the extended end thereof, said sleeve being shorter than said shank and rotatable 360° thereon and a detent on said sleeve extending radially therefrom, said detent extending a substantial portion of the circumferential extent of said sleeve, and said detent having a convex surface facing toward the extended end of said shank.

3. In an introducer, the combination of an elongated body including a cylindrical shank and a head portion, a shoulder on the body at the junction of the head and shank, the extended end of said head having means for seating a marginal portion of a diaphragm, a sleeve mounted on said shank and removable from the extended end thereof, said sleeve being shorter than said shank and rotatable 360° thereon, and a plurality of detents on said sleeve spaced axially therealong and extending radially therefrom, each of said detents extending a substantial portion of the circumferential extent of said sleeve, and each of said detents having a convex surface facing toward the extended end of said shank.

4. In an introducer, the combination of an elongated body including a cylindrical shank and a head portion, a shoulder on the body at the junction of the head and shank, the extended end of said head having means for seating a marginal portion of a diaphragm, a sleeve mounted on said shank and removable from the extended end thereof, said sleeve being shorter than said shank and rotatable 360° thereon, a detent on said sleeve extending radially therefrom, said detent extending a substantial portion of the circumferential extent of said sleeve, and said detent having a convex surface facing toward the extended end of said shank and a lug on said sleeve on the end thereof adjacent the extended end of said shank, said lug extending radially from said sleeve.

5. In an introducer, the combination of an elongated body including a cylindrical shank and a head portion, said head portion being disposed at an angle to said shank, the extended end of said head portion having a socket portion formed therein, a transverse shoulder on the body at the junction of the head and shank, a sleeve mounted on said shank and removable from the extended end thereof, said sleeve being shorter than said shank and rotatable 360° thereon, and a detent on said sleeve extending radially therefrom, said detent extending a substantial portion of the circumferential extent of said sleeve, and said detent having a convex surface facing toward the extended end of said shank.
